UNITED STATES PATENT OFFICE.

JOHN R. CALDERON, OF CHICAGO, ILLINOIS.

ANCHOR PLATE.

Application filed August 25, 1922. Serial No. 584,164.

To all whom it may concern:

Be it known that I, JOHN R. CALDERON, a citizen of the United States, residing at Chicago, in the county of Cook and State 5 of Illinois, have invented certain new and useful Improvements in Anchor Plates, of which the following is a specification.

The present invention relates to anchor plates.

10 More particularly the present invention relates to means for anchoring the rails to the ties in railroad construction and has for one of its objects the provision of efficient rail anchoring means, combined with means 15 for anchoring the spikes which are ordinarily used in securing the rails to the ties.

A further object is to provide anchoring means for railroad ties which is cheap to manufacture and simple to install.

20 A further object is to provide anchoring means which may be readily applied either to new construction or to rails which are already in place.

25 Further objects will appear as the description proceeds.

Referring to the drawings—

Figure 1 is a plan view showing part of a rail, part of a tie and one embodiment of the improved anchor plate, said anchor plate 30 being shown in an intermediate position, occupied when said anchor plate is being installed;

Figure 2 is a plan view similar to Figure 1 but showing the anchor plate in its anchoring position;

Figure 3 is a sectional view taken along the line 3—3 of Figure 2;

Figure 4 is a view in side elevation of the structure illustrated in Figure 2;

40 Figure 5 is a sectional view taken along the line 5—5 of Figure 2; and

Figures 6, 7 and 8 are views of a modified form of the present invention.

The railroad tie is indicated by the numeral 10, while the numeral 11 indicates a rail supported by said tie.

A great number of devices have been tried for securing rails to the ties, the most common expedient being to merely drive spikes 50 into the ties, said spikes having overhanging heads engaging with the lower flange of the rail. Passage of heavy trains over the rails has the effect of loosening said spikes, requiring constant attention in keeping the 55 rails in proper position.

The rail 11 is provided with the flanges

12—12. Underlying the flanges 12—12 is the anchor plate 13, which anchor plate should be of tough metal whereby to withstand severe shocks. Said anchor plate 13 60 comprises the bed portion 14 adapted to lie upon the top of the tie 10, the illustrated anchor plate being provided with a downwardly extending pin 15 on the under side of its bed portion, which pin is adapted to 65 project into the tie and form a pivot point for a tie plate. The bed portion 14 is recessed as indicated by the numeral 14' to avoid high spots which would interfere with the functions of the device. The anchor 70 plate may be of general rectangular conformation in plan view and will be provided, near diagonally opposed corners, with upwardly projecting flanges 16—16, which flanges are provided with recesses, the top walls of said recesses being indicated by the numerals 17—17. As will be pointed out hereinafter, the recesses referred to are adapted to receive the heads of railroad 75 spikes and the walls 17—17 are adapted to 80 overlie and therefore provide abutting means to prevent the loosening of said spikes from the ties. The flanges 16—16 have walls 18—18 which act as stops adapted to abut against the flanges 12—12 of the rail under certain conditions. Said walls 18—18 thus provide limiting means for rotary 85 movement of the anchor plate relative to the rail, permitting said anchor plate to assume the position illustrated in Figure 1, 90 for a purpose which will be referred to hereinafter. Located in the bed portion 14 of the tie plate are the slots 19—19 which may be of arcuate conformation having as their common center the center of the bed 95 portion 14. Said holes have angular end walls, as indicated by the numerals 20—20, to conform to the sides of the ordinary railroad spike, which is rectangular in cross section. When the anchor plate is in the 100 position indicated in Figure 1, the angular ends of the arcuate slots 19—19 provide locating means for the railroad spike, whereby the spike may be driven into the tie in a position adjacent to the sides of the 105 rail, the spikes being indicated by the numeral 21, each of said spikes comprising the shank 22 and the head 23. The shank 22 of each spike 21 lies in proximity to the side of a flange 12 of the rail, while the head 23 110 of each of said spikes overlies a flange 12 whereby to hold the rail tightly in engage-

ment with the bed portion 14. Each flange 16 overlies only a part of its corresponding arcuate slot 19 whereby a spike may be driven into said hole in one position of the 5 anchor plate, said spike underlying the wall 17 of flange 16 in another position of said anchor plate.

The arcuate slots 19-19 should be of sufficient length to permit the driving of the 10 anchor plate with a rotary movement to a position such as indicated in Figure 2, in which the walls 17-17 of the flanges 16-16 overlie the heads 23 of the spikes 21. In order to hold the anchor plate in its normal 15 position, that is, the position indicated in Figure 2, said anchor plate may be grooved longitudinally whereby to provide the shoulders 24-24, which shoulders receive between them the flanges 12-12 constituting 20 the base of the rail. If preferred, spikes 21'-21' may be driven through suitable apertures in the anchor plate 13 to aid shoulders 24-24 in preventing an accidental 25 rotary movement of said anchor plate. If desired, the downwardly extending pin 15 may be omitted, inasmuch as the anchor plate may be given its desired rotary movement without having its center of rotation 30 fixed.

35 The method of installation and the functions of the embodiments of the present invention illustrated in Figures 1 to 5 will be clear without detailed explanation. It may be stated briefly, however, that the anchor plate will be placed upon a tie with the pin 15 embedded in said tie at the proper point to permit the necessary rotary movement of the anchor plate. The anchor plate will be placed in the position indicated in 40 Figure 1, in which the walls 18 of the flanges 16 lie in engagement with the sides of flanges 12-12 of rail 11. End walls 20-20 of the arcuate holes 19-19 will constitute locating means for the spikes 21-21, which 45 spikes may be driven into the tie in proximity to the sides of the flanges 12-12 and overlying the tops of said flanges 12-12. The anchor plate may then be struck with a sledge, being given a movement of rotation 50 to a position in alignment with the rail whereby the top walls 17-17 of the flanges 16-16 of the anchor plate will overlie the heads 23-23 of the spikes 21. The flanges 12-12 will assume a position between the 55 shoulders 24-24 of the anchor plate and said anchor plate will be securely locked in position. Spikes 21'-21' will ensure this locking action. By reason of the holding effect of flanges 16-16 it will be impossible 60 for the spikes 21-21 to work out of the ties. The upstanding walls of flanges 16-16 also prevent the spikes 21-21 from bending or having their heads forced back, which is a common occurrence in track work.

65 The present invention, therefore, provides

means for preventing the "heading" or "shearing" off of the heads of the spikes.

When it is desired to remove the anchor plate illustrated in Figures 1 to 5 from beneath a rail, said operation may be accomplished by slightly raising the rail, by means of a crow bar or other means, and, the spikes 21'-21' having been removed, giving the anchor plate a blow with the sledge whereby to drive said anchor plate to the 70 position indicated in Figure 1, after which the spikes 21-21 may be pried loose. If it is desired to install the anchor plate without removing the rails from said ties, or if it is desired to remove the anchor plate from a rail without removing said rail, either operation may be accomplished by lifting the rail a sufficient distance to allow the tops of flanges 16-16 to pass beneath said rail. The flanges 16-16 need be of only relatively 75 small height, so that the distance which the rail need be lifted is relatively small.

According to the modified form of the present invention illustrated in Figures 6, 7 and 8, the locking plate is moved to or from locking position relative to the spikes by a movement longitudinally of the rail. The anchor plate illustrated in Figures 6, 7 and 8 are indicated by the numeral 25, 80 which anchor plate may be of general rectangular conformation in plan view and may be provided with the shoulders 26-26, which receive between them the flanges 12-12 of the railroad rail. The anchor plate 25 is provided with upstanding flanges 27-27 located upon the shoulders 26-26, each of said flanges 27 being recessed to provide a top wall 28 and an end wall 28'. The anchor plate is provided with slots 29-29 85 extending therethrough, there being a slot 29 for each flange 27 and the design being such that each flange 27 covers one end only of its corresponding slot 29. Each flange 27 is adapted in one longitudinal position of anchor plate 25 to overlie and securely hold 90 in place a corresponding spike 30 located within the corresponding slot 29. When the anchor plate is in a different position longitudinally of the rail, the spikes 30-30 may be driven into the tie through slots 29-29 95 without interference with flanges 27-27. The position of the anchor plate 25 permitting driving of the spikes 30-30 without interference is indicated in Figure 6. Figure 7 represents the position of the anchor plate 25 in which the flanges 27-27 overlie the spikes 30-30 and securely hold same in 100 position. Spikes 31-31 may be driven through suitable holes in the anchor plate 25 after said anchor plate has been moved to the position shown in Figure 7, whereby to prevent said anchor plate from creeping 105 longitudinally of the rail.

In installing the form of the present invention shown in Figures 6, 7 and 8, the 110

anchor plate 25 will be placed upon the tie in a position underlying the rail. The anchor plate will be displaced a short distance from its desired home position in a direction 5 longitudinally of said rail and spikes 30—30 will be driven through the slots 29—29 at those ends of said slots which are not covered by flanges 27—27. After the spikes 30—30 have been driven into the tie, the 10 anchor plate may be struck with a sledge, moving same longitudinally of the rail to the position indicated in Figure 7, in which the end walls 28'—28' of flanges 27—27 abut against spikes 30 and top walls 28 securely 15 hold the spikes 30—30 against loosening. The flanges 27—27 will also prevent movement of the heads of the spikes 30 in a direction laterally of the rail. Spikes 31—31 may now be inserted, to prevent creeping 20 action of the anchor plate longitudinally of the rail.

The chosen embodiments of the present invention have been taken merely for the purpose of illustration and should not be 25 considered in a limiting sense. Many modifications will occur to those skilled in the art. It is intended in this patent to cover all such modifications that fall within the scope of the invention as defined by the 30 appended claims.

I claim:

1. An anchor plate comprising a member 35 adapted to underlie a rail and having a holding position relative thereto, said member being provided with means for limiting the swinging movement thereof from said holding position and having means integral therewith for locating and holding a rail spike.

2. An anchor plate comprising a member 40 adapted to underlie a rail and having a holding position relative thereto, means for limiting rotary movement of said anchor plate from said holding position when applied to 45 a rail, said member being provided with spike locating means, said anchor plate being provided with a portion for overlying and holding said railroad spike in a certain position of said anchor plate.

3. An anchor plate comprising a member 50 adapted to underlie a rail, and opposed means adapted in one position of said anchor plate to locate the positions for driving spikes and in another position of said anchor plate to overlie said spikes to hold said spikes against a loosening movement.

4. In combination, a railroad tie, a rail, 55 an anchor plate mounted between said tie and rail, said anchor plate having a holding position and being provided with means for limiting the swinging movement thereof from said holding position, said anchor plate having means for locating and holding a rail spike.

5. In combination, a railroad tie, a rail,

and an anchor plate lying between said tie and rail, said anchor plate having a holding position and being provided with means for limiting rotary movement thereof from said holding position, said anchor plate being 70 also provided with spike locating means and with a portion for overlying and holding a railroad spike.

6. In combination, a railroad tie, a rail, 75 and an anchor plate lying between said tie and rail, said anchor plate being provided with means for limiting rotary movement thereof, said anchor plate being provided with means for locating a spike when said anchor plate is at one limit of its rotary 80 movement and being also provided with a portion for overlying and holding said spike when said anchor plate is at the opposite limit of its rotary movement.

7. In combination, a railroad tie, a rail, 85 and an anchor plate, said anchor plate being provided with opposed means adapted in one position of said anchor plate to locate holding spikes and in another position of said anchor plate to overlie said spikes to hold 90 said spikes against a loosening movement.

8. An anchor plate comprising a bed portion provided with parallel shoulders adapted to receive between them a railroad rail, and having opposed arcuate slots adapted to 95 receive railroad spikes and also being provided with opposed means for overlying and holding said spikes.

9. An anchor plate comprising a bed 100 member for carrying a railroad rail, said bed member having parallel shoulders for receiving between them the bottom of said rail, said bed plate being provided with opposed arcuate slots adapted to receive railroad spikes and being also provided with 105 spike holding means which overlie a portion only of each of said slots.

10. An anchor plate comprising a bed member having a downwardly extending 110 pivotal point and arcuate slots having said point as a center, said anchor plate being provided with means for limiting swinging movement of said anchor plate and being also provided with spike holding means overlying portions of said arcuate slots.

11. An anchor plate adapted to lie between a railroad tie and a rail, said anchor plate comprising a bed member having a centrally located downwardly extending point providing pivotal means for said anchor plate, said anchor plate having shoulder means on its upper surface for engaging a rail to hold said anchor plate against skewing.

12. An anchor plate adapted to lie 125 between a railroad tie and a rail, said anchor plate comprising a bed member having a centrally located downwardly extending point providing pivotal means for said anchor plate, said anchor plate being provided

with rail engaging means for preventing skewing of said anchor plate.

13. In combination, a railroad tie, a rail, and an anchor plate for said rail, said anchor plate comprising a bed member having a downwardly extending pin adapted to provide pivotal means for said anchor plate, said anchor plate being provided with means for preventing skewing effect and with spike holding means for preventing the upward movement of railroad spikes.

14. In combination, a railroad tie, a rail, and an anchor plate, said anchor plate being provided with a downwardly extending portion providing pivotal means for said anchor plate, means for limiting rotary movement of said anchor plate for attaching purposes and spike locating purposes and means for preventing rotary movement of said anchor plate operative when said anchor plate is in holding position.

15. In combination, a railroad tie, a rail, and an anchor plate, said anchor plate being provided with a downwardly extending portion providing pivotal means for said anchor plate, means for limiting rotary movement of said anchor plate for attaching purposes and spike locating purposes and means for preventing rotary movement of said anchor plate operative when said anchor plate is in holding position, said anchor plate being provided with opposed arcuate spike receiving slots, and spike holding means overlying portions of said slots.

16. An anchor plate comprising a portion adapted to underlie a railroad rail, said anchor plate being provided with slots adapted to receive railroad spikes, said anchor plate having a holding position relative to said rail and being provided with means for limiting movement relative to said rail, said anchor plate having holding means overlying a portion only of said slots whereby spikes may be inserted in said slots and whereby, by shifting movement of said anchor plate, said holding means may be brought to a position overlying and holding said spikes.

17. An anchor plate comprising a bed portion having elongated closed spike locating slots adapted to receive spikes and having spike-holding means overhanging a portion only of said slots.

18. An anchor plate having a pair of parallel shoulders adapted to enclose the base of a railroad rail to lock said anchor plate against skewing movement when said anchor plate is weighted down by said rail and stop members adapted to permit a predetermined skewing movement of said anchor plate relative to said rail under other conditions, said anchor plate being provided with slots and overhanging means, said overhanging means covering a part only of each of said slots.

19. An anchor plate comprising a base and upwardly projecting means, said base being provided with slots for the reception of railroad spikes, said upwardly projecting means covering a part only of each of said slots, said anchor plate having a holding position, said upwardly projecting means having a portion for limiting the skewing movement of said anchor plate relative to a railroad rail from said holding position.

20. An anchor plate comprising a base member, said member being provided with spike locating slots for the reception of railroad spikes, said member being also provided with holding means permitting the insertion of spikes in said slots but overlying and holding said spikes in another position of said member.

21. In combination, a railroad tie, a rail, and an anchor plate for said rail, said anchor plate being shiftable relative to said rail and being provided with slots permitting the insertion of spikes and marking the positions for said spikes on the two sides of said rail when said anchor plate is in one position and overlying and holding said spikes when said anchor plate is in another position.

22. In combination, a railroad tie, a rail, and an anchor plate, said anchor plate having a holding position and being capable of rotary movement relative to said rail, means for limiting such rotary movement from said holding position and means operative when said members are assembled to prevent such rotary movement.

23. An anchor plate, comprising a member adapted to underlie a rail and having a holding position relative thereto, said member being provided with means integral therewith for locating and holding a railroad spike.

24. An anchor plate, comprising a member adapted to underlie a rail and having shoulder means for enclosing the base of said rail, said anchor plate having means integral therewith for locating and holding a rail spike.

25. An anchor plate, comprising a member adapted to underlie a rail and having a holding position relative thereto, said member being provided with means for locating a railroad spike and holding the head thereof from movement either vertically or laterally of said rail.

26. An anchor plate, comprising a member adapted to underlie a rail and having a holding position relative thereto, said member being provided with means integral therewith for locating a railroad spike and for holding the head thereof against movement vertically and laterally relative to said rail.

27. An anchor plate, comprising an an-

chor plate adapted to underlie a rail and having shoulder means for enclosing the base of said rail, said anchor plate having means for locating a railroad spike and for holding said spike against movement either vertically or laterally with reference to said rail.

28. An anchor plate, comprising a member adapted to underlie a rail and having shoulder means for enclosing the base of said rail, said anchor plate having means integral therewith for locating a railroad spike and for holding said spike against movement either vertically or laterally with reference to said rail.

29. An anchor plate, comprising a bed portion having elongated, closed spike locating slots adapted to receive spikes and

having spike holding means overhanging a portion only of said slots, said spike holding means having a portion to hold spikes against a bending movement.

30. An anchor plate, comprising a base member, said member being provided with spike locating slots for the reception of railroad spikes, said member being also provided with holding means permitting the insertion of spikes in said slots but overlying said spikes in another position of said member, said holding member comprising means for holding said spikes against movement vertically and laterally relative to said base member.

Signed at Chicago, Illinois, this 18th day of August, 1922.

JOHN R. CALDERON.
